US0D1053820S

(12) **United States Design Patent** (10) Patent No.: **US D1,053,820 S**
(45) Date of Patent: ** Dec. 10, 2024

(54) **PLUG**

(71) Applicant: **NAMI.AI PTE Ltd.**, Duxton Hill (SG)

(72) Inventor: **Wang Chunyi**, Shanghai (CN)

(73) Assignee: **NAMI.AI PTE Ltd.**, Singapore (SG)

(**) Term: **15 Years**

(21) Appl. No.: **29/856,692**

(22) Filed: **Oct. 17, 2022**

(30) **Foreign Application Priority Data**

Apr. 15, 2022 (CN) 202230211717.6

(51) **LOC (14) Cl.** **13-03**

(52) **U.S. Cl.**
USPC **D13/137.1**

(58) **Field of Classification Search**

USPC D13/137.1–137.4, 138.1–138.2, 139.8,
D13/199

CPC H01R 13/6675; H01R 11/00; H01R 9/00
